UNITED STATES PATENT OFFICE.

GLENN W. WILLARD, OF ALBANY, OREGON.

CARRIER.

1,179,258.

Specification of Letters Patent. Patented Apr. 11, 1916.

Application filed January 20, 1914. Serial No. 813,265.

To all whom it may concern:

Be it known that I, GLENN W. WILLARD, a citizen of the United States, residing at Albany, in the county of Linn and State of Oregon, have invented new and useful Improvements in Carriers, of which the following is a specification.

The invention relates to a carrier, and more particularly to the class of cases for use by mail carriers in rural districts.

The primary object of the invention is the provision of a case wherein the equipment ordinarily required by a mail carrier in a rural district can be conveniently held so as 15 to be readily accessible for use, the case being novel in form to render it compact, handy and useful.

Another object of the invention is the provision of a case which is simple in construction, strong, durable, reliable and efficient in its purpose, and inexpensive in manufacture.

With these and other objects in view, the invention consists in the construction, combination and arrangement of parts as will be hereinafter fully described, illustrated in the accompanying drawings, and pointed out in the claim hereunto appended.

In the drawing:—Figure 1 is a perspective view of a case constructed in accordance with the invention. Fig. 2 is a similar view showing the case open. Fig. 3 is a vertical longitudinal sectional view thereof.

Similar reference characters indicate corresponding parts throughout the several views in the drawing.

Referring to the drawing in detail, the case comprises an oblong body 5 preferably constructed from leather, although it may 40 be made from any other suitable material, formed in one side and at the top thereof with an opening 6 so that access may be had to the interior thereof. The open side of the body 5 is extended to form a swinging closure section 7 for the opening 6, and this section is provided with end flap 8 and a securing flap 9 so that the said opening 6 can be completely closed. Mounted on the opposite side of the body 5 is a catch device 10 which engages a loop 11 carried on

the flap 9 to fasten the swinging section when closed. Mounted on the inner face of the swinging section 7 is a pocketbook 12 which is adapted for use in holding money, while arranged interiorly of the body are a 55 series of partitions 13 forming independent compartments or pockets 14, each varying in length with respect to the other, for receiving a receipt book, envelops, stamp book, and application blanks, which are included 60 in the equipment of a mail carrier in rural districts, it being apparent that on the opening of the swinging section 7 access will be had to the pockets 14 so that the equipment or the contents thereof can be readily removed for use.

Fixed to opposite end walls of the body 5 are the ends of a hand strap 15 so that the case can be conveniently carried by the user. This strap 15 is of a length so as not to interfere with the opening of the swinging section 7 or the closing thereof.

In constructing the body 5 with the opening 6 in the top and side thereof the upper portion of the said body is tapered as shown, 75 thus giving a neat appearance thereto and avoiding it being rendered bulky.

What is claimed is:—

A carrier of the class described comprising a body having an opening extended 80 throughout the top and for substantially one-half of the length of the side diagonally of the same, a cover hinged to the body for closing the opening and adapted to rest against the remaining portion of said side 85 when swung in a position for uncovering the opening, a pocket book confined within the cover and adapted to be brought to inverted position when the said cover is at rest against the side of the body, a plurality 90 of partitions within the body and forming compartments therebetween, said partitions being of varying heights with respect to each other, and a flap on the cover.

In testimony whereof I affix my signature 95 in presence of two witnesses.

GLENN W. WILLARD.
